W. M. Wilson

UNITED STATES PATENT OFFICE

JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK

INDICATING DEVICE

Application filed January 15, 1927. Serial No. 161,334.

This invention relates to clocks and more particularly to clocks of the non-pendulum type such as escapement spring clocks and the like.

In the ordinary non-pendulum type of clocks in order to ascertain whether the clock is functioning it is usually necessary for an observer to watch the clock until he sees the hands move. This method utilizes time and also is very tedious.

My invention provides a type of pendulum consisting of a pendulum arm and a target or indicator which may be viewed through a small aperture in the dial of the clock.

For the purpose of clearly illustrating my invention I have shown it as applied to a secondary clock.

An object of my invention is to provide an improved and simplified means by which an observer may ascertain whether a clock of the non-pendulum type is functioning.

Another object is to provide an indicating pendulum for a non-pendulum type of clock actuated by the clock mechanism.

Other objects and advantages of my invention will be obvious from the following particular description embodying the invention and of the accompanying drawing in which

Fig. 1 is a front elevational view of a secondary clock showing my pendulum device applied thereto and also the aperture through which the indicator on the pendulum may be viewed.

Fig. 2 is a rear elevational view of a secondary clock mechanism with parts omitted and disclosing means for operating the pendulum.

Fig. 3 is a fragmentary side elevational view partly in section showing the pendulum mechanism.

Fig. 4 is a perspective of the upper portion of the pendulum mechanism shown in Fig. 2 disclosing the means for hanging same on the clock.

Referring more particularly to the drawing, the operation of my pendulum mechanism may be readily understood from Fig. 2 in which is disclosed a secondary movement. The motive power for actuating the secondary

movement comprises a magnet 1 coacting with an armature 2 pivoted at 2c and held away from the cores of the magnet by spring 3. Energization of magnet 1 attracts the armature 2 which has affixed thereto an arm 2a on which is pivotally mounted at 2b an actuating pawl 4. This pawl normally rests in one of the notches at 4a of the ratchet wheel 5 and as soon as the armature 2 is attracted by the magnet 1 the pawl is carried into the next or adjacent notch. Upon deenergization of the magnet the armature 2 returns to its normal position under the influence of its spring 3, rotating the ratchet wheel 5 a distance of one notch. A retaining pawl 6, biased by a spring 7 is provided to hold the ratchet wheel 5 in the position to which it has been turned by the actuating pawl 4. Associated with the ratchet wheel 5 is the usual clock mechanism including reduction gearing etc. for operating the hands of the clock.

Referring now also to Fig. 3 my indicating pendulum mechanism is disclosed as comprising a pendulum arm 8 to which is affixed at its lower end a pendulum weight forming a target or indicator 9 which may be viewed by an observer through an aperture 10 in the dial of the clock (see Figs. 1 and 3) indicating whether the clock is running. Fixed at 11 to the supporting plate 12 of the clock is a stud 13 which has knife edges 14 and 14' respectively (see Figs. 3 and 4) upon which the arms 15 and 15' of the pendulum arm 8 rest. An extension arm 16 fixed to the pendulum arm 8 is provided with an adjusting counterbalance weight 17 (see Figs. 2, 3 and 4). This weight is simply provided for balancing the target or indicator 9.

Fixed to the armature 2 by means of a screw 18 is an upwardly extending rod 19 which is bent at its upper end so that the lateral projection 20 lies at right angles to the pendulum 8 and will, when the arm 19 is actuated strike the pendulum arm 8 at 21 causing the pendulum to oscillate. The magnet 1 is energized often enough so that these impacts will keep the pendulum 8 continually oscillating as long as the secondary clock is running.

In order that the motion of the indicator or target 9 may be readily visible it may bear a color contrasting with the color of the dial or any other suitable arrangement may be employed for showing that the target is in motion.

My invention is capable of a wide variation and relationship of parts without departure from the nature and principle thereof, and I do not restrict myself unessentially in the foregoing or other particulars, but contemplate such alterations and modifications within the scope of the appended claims as may be found advisable.

I claim:

- 15 1. In a clock having a dial, indicating hands cooperating therewith, and magnetic means for moving the hands; means for indicating that the clock is running, said indicating means comprising an element substantially free of effect on the indicating hands, and means operated by said magnetic means for regularly, periodically actuating said element.
- 25 2. In an instrument having an electrical source, a magnet for receiving periodic impulses from said electrical source, time indicating devices operated entirely under control of said magnet; means for indicating that the magnet is receiving said impulses, said means comprising a pendulous element and means operated by the magnet for periodically moving said element, said element being independent of the electrical source and ineffective to control the reception of impulses by the magnet.
- 35 3. In a time indicating mechanism, a dial and time indicating hands cooperating therewith, magnetic means for advancing said indicating hands, a periodic timed impulse source external to said indicating mechanism, said magnetic means receiving timed period impulses from said source, an indicating device actuated by the advancing action of said magnetic means, said indicator being mounted to swing freely under the action of gravity during the quiescent period of the time indicating mechanism.
- 45 4. In an electric clock, time indicating means, magnetically operated mechanism for periodically advancing said time indicating means, a source of periodic electric impulses, a driving magnet therefor energized by said periodic electric impulses, and an indicating device controlled by said magnet to operate during the period of inactivity of said magnetically operated mechanism to indicate that the magnet is receiving said periodic impulses.
- 55 5. In an electric clock, a dial and time indicating hands associated therewith, a magnetically operated mechanism for advancing the time indicating hands, an oscillating pendulous member periodically actuated by the periodic operation of the magnetically

operated mechanism and oscillating freely under influence of gravity between such periodic actuation.

In testimony whereof I hereto affix my signature.

JAMES W. BRYCE.
